UNITED STATES PATENT OFFICE.

ARTHUR P. CURTIS, OF FULTON, NEW YORK, ASSIGNOR TO THE HUNTER ARMS CO., OF FULTON, NEW YORK, A CORPORATION OF NEW YORK.

ACTION FOR BREAKDOWN GUNS.

1,160,581.

Specification of Letters Patent. Patented Nov. 16, 1915.

Application filed March 28, 1913. Serial No. 757,328.

To all whom it may concern:

Be it known that I, ARTHUR P. CURTIS, a citizen of the United States, and a resident of Fulton, in the county of Oswego and State of New York, have invented a new and useful Action for Breakdown Guns, of which the following is a specification.

This invention has for its object the production of an action for firearms which is particularly simple in construction, economical in manufacture, and highly efficient and durable in use; and the invention consists in the combinations and constructions hereinafter set forth and claimed.

15 In describing this invention reference is had to the accompanying drawing in which like characters designate corresponding parts in all the views.

Figure 1 is a side elevation of a breakdown gun embodying my invention, the side plate being removed and the stock and barrel being broken away, and the cocking lever being shown partly in section. Fig. 2 is a view similar to Fig. 1 illustrating the 25 position of the parts when the gun is broken open, the fore-end being partly broken away to illustrate the means for transmitting the movement of the barrel to the cocking lever.

30 This action for firearms comprises, generally, means for cocking the hammer and for actuating the hammer when the trigger is pulled. The action is particularly applicable for break-down guns and is here shown 35 as applied to a break-down gun.

1 is the frame of the firearm, 2 is the barrel hinged at 3 to the frame in the ordinary manner, and 4 is the fore-end.

5 is the hammer, 6 the firing pin, 7 the 40 sear, 8 the sear spring, and 9 the trigger, of the action or firing mechanism, all of which parts may be of any desirable form, size and construction, although I have shown a particular form of firing pin which constitutes the subject matter of another application. The hammer also embodies certain features peculiar to this invention which features will be hereinafter described. The 45 means for cocking and actuating the hammer also includes mechanism for transmitting the break-down or pivotal movement of the barrel 2 to the hammer through the main spring. As here shown, this mechanism includes a lever 10 pivoted to the forward ex-

tension 11 of the frame beneath the barrel 2, it being here shown as extending lengthwise of the gun, and pivoted by a horizontal pivot 12 intermediate of its ends in a recess in the side of said forward extension, and as having its forward arm extending in front of the pivot 3 of the barrel in position to coact with a shoulder at the rear end of the fore-end 4. The rear arm of said lever is provided with means coacting with the hammer to cock the hammer and actuate the 65 same. Owing to the simplicity of the lever and associated parts, it is interchangeable, that is can be used on either the right or left side of the gun.

The shoulder provided at the rear end of 70 the fore-end 4 is usually a wall 13 of a socket 14 in the rear end of the fore-end into which socket the front end of the lever 10 extends. The rear arm of the lever is formed with a socket 15 in which the main 75 spring as a coil spring 16 is located, the main spring acting on a part as a plunger 17 slidable in the socket 15 and pressed by the main spring into engagement with a cam surface 18 provided on the tail 19 of the 80 hammer 5. The lever 10 serves as a carrier for the main spring and is operated to tension the main spring or cock the hammer by the action of the barrels 2. As here shown the tail is located in front of and below the 85 pivot 20 of the hammer and on the opposite side of the pivot 20, along a diameter, to that on which the head of the hammer is located. The cam surface 18 as shown is concave and extends across said diameter and also above 90 and below a straight line passing through the axes 12 and 20 and is nearly concentric with the axis 12 when the hammer is cocked, and the spring pressed plunger 17 is normally engaged when the hammer is cocked 95 as shown in Fig. 1, with the cam surface below said diameter and line, and during the movement of the hammer toward the firing pin 6 under the impulse of the spring 16, the spring 16 expands or extends and holds 100 the plunger 17 engaged with the lower end of the surface 18, that is, the end of the tail 19. When the hammer is down the upper portion of the cam surface 18 is nearer the axis 12, than the lower portion of said surface 18. 105

During the breaking down of the gun, that is, during the relative movement of the

frame 1 and barrels 2 about the axis 3, the shoulder 13 of the fore-end presses against the front end of the lever 10 and moves the front end of the lever downwardly on its pivot and the spring pressed plunger upwardly along the cam surface 18 toward the diameter and center line before referred to, first causing the plunger 17 to be pushed back into the socket 15, and the spring 16 to be tensioned. Further movement of the lever causes the plunger to move across said line and cock the hammer, the spring 16 expanding to effect the cocking of the hammer. The cam surface is now again nearly concentric with the axis of the lever 12. Upon the return movement of the barrel 2 about its axis 3, the lever is returned to its starting position, Fig. 1, the spring 16 being again tensioned, the plunger 17 moving downwardly along the cam 18. The cam surface 18 is not exactly concentric with the axis 12 but the upper portion is farther away slightly than the lower portion when the hammer is cocked.

The breaking down of the gun is normally prevented, that is, the frame and barrel are held in their normal positions as shown in Fig. 1, by the usual bolt mechanism consisting of a top lever 21 which operates a bolt which takes into a notch 22 in a lug 23 at the rear end of the barrel 2.

The firing pin 6 is of the form indicated in dotted lines and instead of being held in its guide passage in the frame by a screw, pin or other fastening means, is held in position by the side plate, the passage for the firing pin being so located that an edge of the side plate extends partly across the rear end of the said passage for the firing pin, so as to engage the rear end of the firing pin.

The firing pin and the means by which it is held in position forms the subject matter of another application.

What I claim is:

1. In a break-down gun, the combination with a frame and a barrel hinged to the frame, of firing mechanism including a hammer, and means for cocking the hammer during the breaking down or pivotal movement of the barrel, said means including a power-transmitting lever between the barrel and the hammer, the lever being pivoted intermediate of its ends to the frame, and having one arm thereof arranged to receive movement from the barrel, the other arm thereof being provided with a part coacting with the hammer, and a spring for pressing said part into engagement with the hammer and for actuating the hammer upon the pull of the trigger, substantially as and for the purpose set forth.

2. In a break-down gun, the combination with a frame and a barrel hinged to the frame, of firing mechanism including a ham-

mer, and means for cocking the hammer during the breaking down or pivotal movement of the barrel, said means including a power-transmitting lever between the barrel and the hammer, the lever being pivoted 70 intermediate of its ends to the frame by a horizontal pivot, the lever extending forwardly and rearwardly and having its forward arm arranged to receive movement from the barrel and its rear arm being provided with a part coacting with the hammer, and with a spring for pressing said part into engagement with the hammer, the spring serving as a main spring for actuating the hammer, substantially as and 80 for the purpose described.

3. In a break-down gun, the combination of firing mechanism including a hammer having a cam surface on the side of the axis thereof, along a diameter, opposite to 85 that on which the head of the hammer is located, said surface extending crosswise of said diameter, a main spring, a part acted on by the main spring and engaging said cam surface on one side of said diameter 90 when the hammer is cocked, and a carrier for the main spring and said part, the carrier being operable to move said part along the cam surface toward said diameter to first tension the spring when the hammer 95 is down and then across said diameter, substantially as and for the purpose described.

4. In a break-down gun, the combination of firing mechanism including a hammer having a tail provided with a forwardly 100 facing concave cam surface, a main spring, a part acted on by the main spring and coacting with said surface and normally engaging said surface at the lower end thereof, and a pivoted carrier for the spring and 105 said part, the cam surface being arranged nearly concentric with the axis of the carrier when the hammer is cocked, and the carrier being operable when the hammer is down to move said part upwardly along said 110 cam surface to first tension the spring, then above the axis of the hammer to permit the spring to expand and cock the hammer, and then back along said cam surfaces to again tension the spring, substantially as and for 115 the purpose specified.

5. In a break-down gun, the combination with a frame, and a barrel hinged to the frame, of firing mechanism including a hammer having a tail provided with a cam 120 surface, means for transmitting the breaking down movement of the barrel to the hammer, said means including a lever having one end arranged to receive movement from the barrel and having its other end 125 provided with means for coacting with said cam surface, the cam surface being concave and extending above and below a straight line passing through the axes of the lever and hammer, and said surface being ar- 130

ranged nearly concentric with the axis of the lever when the hammer is cocked, substantially as and for the purpose set forth.

6. In a break-down gun, the combination with a frame, and a barrel hinged to the frame, of a firing mechanism including a hammer having a tail provided with a cam surface, means for transmitting the breaking down movement of the barrel to the hammer including a lever pivoted to the frame and arranged to receive movement from the barrel, a main spring carried by the lever and a part carried by the lever and arranged to be acted on by the main spring, and engaged with said cam surface on the tail of the hammer, substantially as and for the purpose described.
7. In a break-down gun, the combination with a frame, and a barrel hinged to the frame, of a firing mechanism including a hammer formed with a tail having a cam surface, and means for cocking the hammer comprising a lever extending lengthwise of the frame and being pivoted between its ends by a horizontal pivot to the frame, and having its front end arranged to receive movement from the barrel during the breaking down movement of the barrel and having its rear end formed with a socket, and a spring pressed plunger located in the

socket and coacting with said cam surface, said surface extending crosswise of a straight line passing through the axes of the hammer and the lever and being normally nearly concentric with the axis of the lever when the hammer is down, the lever being normally arranged to engage said part with the portion of the tail below said line and said part being movable above said line and then to its normal position during the break-down movement of the gun and the return of the barrel to its normal position, substantially as and for the purpose specified.

8. In a firearm, a frame, a hammer, a lever pivoted to the frame and having a coiled spring thereon, the lever being arranged so that the coiled spring acts as the main spring on the hammer and means for moving the lever to compress the spring and cock the hammer, substantially as and for the purpose specified.

In testimony whereof, I have hereunto signed my name in the presence of two attesting witnesses, at Fulton in the county of Oswego, in the State of New York, this 26th day of Feby 1913.

ARTHUR P. CURTIS.
